UNITED STATES PATENT OFFICE

HARRY B. HULL, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed November 30, 1925, Serial No. 72,096. Renewed December 13, 1928.

The present invention invention relates to refrigerators and particularly to refrigerators in which the cabinet thereof is divided into a plurality of compartments.

In certain types of mechanical refrigerator, water is frozen in receptacles and the ice blocks are removed from the receptacles and delivered to an ice storage chamber. One of the objects of the present invention is to simplify this type of refrigerator. One manner of carrying out this object is to form a portion of a partition wall, which divides the refrigerator cabinet into a food compartment and a cooling compartment into a chamber for storing blocks of ice which have been frozen within the cooling chamber.

Another manner of carrying out the above object is to arrange the ice storage chamber in such a position with respect to the other portions of the partition wall that a plurality of air passages, connecting the compartments, can be arranged at different levels with respect to one another whereby natural circulation of air will take place.

Other and further objects of the present invention will be apparent from the following description reference being had to the accompanying drawings wherein a preferred form of embodiment of the present invention is clearly shown.

In the drawings:

Fig. 1 is a sectional view of the cabinet of the improved refrigerator showing a refrigerating machine in elevation.

Fig. 2 is a fragmentary sectional view taken on line 2—2 of Fig. 1.

Fig. 3 is a fragmentary sectional view taken on line 3—3 of Fig. 1, and

Fig. 4 is a front view in elevation showing a door of the cabinet open.

Referring to the drawing, the refrigerator includes a cabinet 20 having a machine compartment 21, a cooling compartment 22 and a food compartment 23. The cooling compartment 22 and food compartment 23 are surrounded by insulation 25, the top portion 25a of the insulation being removable to provide access to the interior of the cooling compartment 22. The cooling compartment 22 is provided with a lining 26 which forms the

back, front and opposite side walls for said compartment. The lower portion of lining 26 extends inwardly to provide a flange 27. The compartment 23 is provided with a lining 29 which forms the bottom, back, front and opposite side walls for said compartment. The upper portion of lining 29 extends inwardly to substantially the same distance as the flange 27 of lining 26 to provide a flange 30.

A partition wall 32 between compartments 22 and 23 is secured to the flanges 27 and 30 by bolts 33 which bolts are also utilized for securing flange 27 to flange 30, there being a gasket 34 interposed between these flanges. The partition wall 32 includes a downwardly extending portion providing a chamber 36 which chamber includes a back wall 37 and a front wall 38, a bottom wall 39, a side wall 40 and an opposite side wall 41.

The refrigerating machine herein shown is substantially the same as that shown and described in the patent to D. F. Keith, 1,510,147 of September 30, 1924, and shown in co-pending application Serial No. 3789, filed January 21, 1925.

For the purpose of this invention it is deemed sufficient to state that this refrigerating machine is of the absorption type including a generator-absorber 43 which is adapted to be intermittently heated and intermittently cooled for intermittently forcing refrigerant therefrom into an evaporator 44 and for withdrawing refrigerant from the evaporator. As is disclosed in the aforementioned patent and application, the entire refrigerating machine is pivotally mounted and the evaporator 44 is adapted to rock from the position shown in full line to the position shown in dotted line. The rocking from the full line position to the dotted line position is caused by the presence of substantially all of the refrigerant in the generator-absorber 43, and, the evaporator is rocked from the dotted line position to the full line position when substantially all of the refrigerant is in the evaporator 44.

Water receptacles 46 are provided in the cooling compartment 22 for receiving water which is delivered to the receptacles 46 in any suitable manner as disclosed in the previous

55

ly mentioned patent and application. Ice pegs 47 attached to the evaporator 44 extend within the water receptacles 46. During the cooling phase of the evaporator 44, heat will be conducted from the water within the receptacles 46 to the evaporator 44 through the pegs 47, in order to freeze the water into ice blocks. After a predetermined period of the refrigerating cycle, the evaporator will move 10 from the position shown in the full line to that shown in the dot and dash line and since the pegs 47 are located at an angle, the ice blocks 49 will be withdrawn from the receptacles 46. When the cooling compartment 15 22 becomes warmer the ice blocks 49 will slide from the pegs 47 and will fall into an ice tray 50 located within the storage chamber 36.

The front wall 38 of the storage chamber 36 is provided with an opening 51 through 20 which the ice tray 50 may be removed. The ice tray has a handle 50^a and a plate 50^b which latter closes the opening 51 when the ice tray is in position in the storage chamber. The front wall 53 of the cabinet 20 is provided 25 with a door opening 54 providing access to the food compartment 23. This door opening 54 is closed by door 55. The storage chamber 36 extends to such a distance within the food compartment 23 that the opening 51 30 of said chamber is in alignment with the door opening 54 whereby the ice trays 50 can be removed through said door opening. By constructing and arranging the elements as previously described, the ice trays are accessible 35 and only one door is necessary to provide access to the food compartment and to the ice trays. Furthermore, the construction of the present refrigerator is relatively simple in that the partition wall between the 40 cooling compartment and the food compartment is also utilized as a storage chamber for ice.

The inclined portion 41^a of side wall 41 of chamber 36 is provided with an opening 45 56 and the partition wall 32 is provided with openings 57 and 58 located at the front and rear of the cabinet and adjacent that side of the compartments opposite from the opening 56 and chamber 36. Since the chamber 36 is 50 located below the other portion of the partition wall 32, the opening 56 is located at a lower level than the openings 57 and 58. These openings being located at different levels, natural circulation of air will take 55 place, the relatively cold air passing from compartment 22 into chamber 36 thence through opening 56 into the compartment 23, and the relatively warm air passing from the compartment 23 through openings 57 and 60 58 and into the compartment 22. However it will be noted that the opening 56 is above the bottom of the ice chamber and to one side of the ice drawer. Consequently the ice drawer is out of the path of air currents 65 circulating thru the openings 57 and

58 and 56. The ice therefore is in a pocket wherein the air is relatively quiet, this pocket being included between the portion of the inclined wall 41^a which is below the opening 56, the opposite side wall 40 and the front 70 and back walls 38 and 37 respectively. The cold air settling in the pocket of the ice chamber 36 will be further chilled and remain around the ice, and prevent the circulating air from causing more rapid melting 75 thereof.

A drain 60 is connected with chamber 36 and extends through the lining 29 and insulation 25 and into the compartment 21. This compartment is provided with a basin 80 61 for receiving water which water is conducted therefrom by a drain 62. All water of condensation which takes place within the compartment 22 will flow into the chamber 36 whence it flows to drain 60 into basin 85 61. Water from the melting ice within tray 50 will also flow from the chamber 36 through the drain 60.

It is apparent from the foregoing description that a relatively simple refrigerator 90 has been provided. The partition wall between the cooling and food compartment provides means for readily draining water of condensation from the cooling compartment and also the melting ice. This partition wall also is formed in such a manner as to provide an ice storage chamber which may be maintained at a relatively low temperature so that the ice blocks are not readily melted, and the construction and arrangement is such that a plurality of air passages are provided between the compartments located at different levels whereby natural circulation of air may take place between the compartments. 100

While the form of embodiment of the present invention as herein disclosed constitutes a preferred form, it is to be understood that other forms might be adopted all coming within the scope of the claims which follow. 105

What is claimed is as follows:

1. Refrigerating apparatus including a cabinet, a partition dividing the cabinet into a cooling compartment and a storage compartment, a door for the storage compartment, a container in the cooling compartment for water to be frozen, means in the cooling compartment for freezing the water, means for removing the ice from the container, and a storage chamber in the cooling compartment arranged to receive ice removed from the container, said chamber projecting into the storage compartment opposite said door. 115

2. Refrigerating apparatus including a cabinet, a partition dividing the cabinet into a cooling compartment and a storage compartment, a container in the cooling compartment for water to be frozen, means in 120

125

130

- the cooling compartment for freezing the water, means for removing the ice from the container and a receptacle in the cooling compartment arranged to receive ice removed from the container the receptacle being removable thru the storage compartment.
3. Refrigerating apparatus including a cabinet, a partition dividing the cabinet into a cooling compartment and a storage compartment, a container in the cooling compartment for water to be frozen, means in the cooling compartment for freezing the water, means for removing the ice from the container, said partition having a storage chamber projecting into the storage compartment and an opening in the wall of the chamber, a receptacle in the storage chamber arranged to receive ice removed from the container, and means attached to the receptacle for closing the opening.
4. A refrigerating apparatus including a cabinet, a partition dividing the cabinet into a storage compartment and a cooling compartment, a door for the storage compartment, a container within the cooling compartment adapted to receive water to be frozen, means within said cooling compartment for freezing the water, means for removing the ice from the container, said partition including a storage chamber projecting into the storage compartment opposite the door and arranged to receive ice removed from the container.
5. A refrigerating apparatus including a cabinet, a partition dividing the cabinet into a storage compartment and a cooling compartment, a container within the cooling compartment adapted to receive water to be frozen, means within said cooling compartment for freezing the water, means for removing the ice from the container, said partition having a pocket arranged to receive ice removed from the container and having a plurality of openings for the circulation of air between the compartments, said pocket being out of the path of currents of air circulating thru said openings.
6. A refrigerating apparatus including a cabinet, a partition dividing the cabinet into a storage compartment and a cooling compartment, a container within the cooling compartment adapted to receive water to be frozen, means within said cooling compartment for freezing the water, means for removing the ice from the container, said partition having a pocket arranged to receive ice removed from the container and having a plurality of openings above the pocket for circulating air between the compartments.
7. A refrigerating apparatus including a cabinet, a partition dividing the cabinet into a storage compartment and a cooling compartment, a container within the cooling compartment adapted to receive water to be frozen, means within said cooling compartment for freezing the water, means for removing the ice from the container, said partition having a pocket arranged to receive ice removed from the container and having a plurality of openings for the circulation of air between the compartments, said pocket being out of the path of currents of air circulating thru said openings.
8. Refrigerating apparatus comprising a cabinet having a cooling compartment and a storage compartment, a door for the storage compartment and an ice chamber in the cooling compartment, said chamber projecting into the storage compartment opposite said door.
9. A refrigerating apparatus including a cabinet, a partition dividing the cabinet into a storage compartment and a cooling compartment, an open container within the cooling compartment for storing ice, said partition having a plurality of openings for the circulation of air between the compartments, and a pocket in said partition arranged to receive said container, said pocket being out of the path of currents of air circulating through said openings.
10. Refrigerating apparatus including a cabinet, a partition dividing the cabinet into a cooling compartment and a storage compartment, a door for the storage compartment, a container in the cooling compartment for water to be frozen, means in the cooling compartment for freezing the water, a storage chamber in the cooling compartment arranged to receive ice removed from the container, said chamber projecting into the storage compartment opposite the door, and means for removing ice from the container and delivering it to the chamber.
11. A refrigerating apparatus including a cabinet, a partition dividing the cabinet into a storage compartment and a cooling compartment, said partition having a plurality of openings for the circulation of air between the compartments, and a pocket in said partition arranged to receive ice, said pocket being out of the path of currents of air circulating through said openings.
12. Refrigerating apparatus including a cabinet having a cooling compartment and a storage compartment, a door for the storage compartment, a container for water to be frozen, an ice storage chamber disposed opposite said door, and means for removing ice from said container and delivering the ice to said ice storage chamber.

In testimony whereof I hereto affix my signature.

HARRY B. HULL.
